United States Patent Office.

CHARLES C. SCAIFE, OF PITTSBURG, PENNSYLVANIA.

Letters Patent No. 91,672, dated June 22, 1869; antedated June 10, 1869.

IMPROVED METALLIC ROOFING.

The Schedule referred to in these Letters Patent and making part of the same.

To all whom it may concern:

Be it known that I, CHARLES C. SCAIFE, of Pittsburgh, in the county of Allegheny, and State of Pennsylvania, have invented certain new and useful Improvements in Metallic Roofing, &c.; and I do hereby declare that the following is a full, clear, and exact description thereof, reference being had to the accompanying drawings, and to the letters of reference marked thereon.

The nature of my invention consists in lining sheet-metal with felt, or its equivalent, substantially in the manner and for the purpose hereinafter described.

To enable others skilled in the art to make and use my invention, I will proceed to describe its construction and operation.

In the accompanying drawings, which form part of my specification—

Figure 1 represents a top view of a corrugated sheet of metal, with a section of another sheet of the same metal overlapping it.

Figure 2 is a longitudinal section of the same, cut through at line x of fig. 1.

Figure 3 is a transverse section of the same, cut through at line x' of fig. 1.

Figure 4 is a transverse section of the same, cut through at line x of fig. 1.

In the drawings—

A represents the sheet-metal, which is made in any of the known forms.

B represents the felt lining of the sheet-metal.

The felt lining B is secured to the sheet-metal by coating the metal with a good article of glue, or other matter suitable for making the felt adhere close and firmly to the sheet-metal.

After the sheet-metal is coated with the matter used for securing the felt to it, the felt is spread over the sheet-metal, and is then pressed down on it, after which it is "set away" to dry.

The advantage of my improvement consists in being enabled, through the medium of sheet-metal lined as hereinbefore described, to make a metallic roof with close joints or seams, as indicated at C, and also to prevent "condensation" on the under side of the roof of the building.

The condensation of the atmosphere in buildings and the "droppings" from the roof, the openings between sheets of metal, admitting dust, cold, and snow-driftings, make the ordinary metallic roof very objectionable, a remedy for which is found in my improvement.

Having thus described the nature, construction, and operation of my improvement,

What I claim as of my invention, is—

Sheet-metal, lined with felting, or its equivalent, substantially as herein described, and for the purpose set forth.

CHAS. C. SCAIFE.
